UNITED STATES PATENT OFFICE.

JAMES DENNIS ROOTS, OF WEST KENSINGTON, LONDON, ENGLAND.

VALVE FOR INTERNAL-COMBUSTION ENGINES.

1,186,836.

Specification of Letters Patent. Patented June 13, 1916.

Application filed May 5, 1913. Serial No. 765,537.

To all whom it may concern:

Be it known that I, JAMES DENNIS ROOTS, a subject of the King of Great Britain, and a resident of 58 Avonmore road, West Kensington, London, W., England, have invented an Improved Valve for Internal Combustion Engines, of which the following is the specification.

This invention relates to an improved valve for internal combustion engines.

The object of the invention is to provide a simple construction of compound or double valve which shall be more silent in operation than other valves of the puppet or mushroom type, and which shall be capable of controlling both inlet and exhaust or two passageways.

It has been shown by experiment that in a four stroke cycle engine about ninety per cent. of the noise produced is caused by the blow on the spindle end of the mushroom or puppet exhaust valve necessary to open it at the end of the working stroke against a pressure in the cylinder of about 50 lbs. per square inch on the top of the valve.

In this invention a balanced valve is employed of such construction that the resistance to lifting at the end of the working stroke is so much reduced as to be practically negligible. This construction of balanced valve is particularly applicable to four stroke cycle engines though it may be employed in two stroke cycle engines.

The valve is preferably formed as a hollow shell or casting adapted to slide as to its lower end in a cylindrical casing which may be formed integrally with the working cylinder, and with the lower of the two walls which inclose the usual lateral channel to, and forming part of the combustion chamber. The upper end of the hollow valve may be provided with a ground surface to find a seating on the upper wall. This may conveniently be for the exhaust or outlet. I may provide a detachable closing disk for the lower end of the valve having a central guide or hole through which the rod operating the valve slides.

The piston end of the valve may conveniently have one or two packing rings fitting grooves in the cylindrical casing. The piston end of the valve has ports which are adapted to be so lifted as to open into the combustion chamber. The lower wall may also be provided with a seating for the valve to fit a similar coned seating to that on

the upper portion of the valve. This seating if employed may be formed with the cone of the seating in the opposite direction to the usual form. The object of this is to provide that the expansion of the valve between the two seatings when heated may be compensated for by the lateral expansion, so that both ground rings may fit their seatings, cold or hot.

In four stroke cycle engines the valve is preferably operated by a cam of the known two step type of suitably curved contour.

When the cam lifts the valve to open the exhaust, the pressures on both portions or ends of the double valve are nearly equal as the diameter of one end is only slightly greater than the other. While the exhaust is taking place the piston valve ports are closed. At the beginning of the suction stroke, the cam lifts the valve further and the valve piston closes the outlet, and the ports in the piston then open communication with the inlet pipe. At the end of the suction stroke the cam quickly closes both inlet and outlet, and the upper and lower ground annular valve surfaces then fit on their seatings, if the lower seating be used. When the lower seating is not employed, the piston rings surrounding the piston valve serve to keep the inlet end tight.

A lever and roller are preferably fitted between the cam and the valve push rod.

The balanced hollow valve with two seatings is preferably formed in two parts, and may be fitted with interior tube bolts or holders between the two seatings, so that the expansion of one tubular connection may be compensated for by the expansion of the other.

The balanced valve when formed in two portions, has the lower part preferably formed with a spider having a central hole resting on a shoulder on the valve stem, and the end of the valve stem screws into or is held in a boss in the upper surface of the other part and so secures the two parts together. An annulus of steel or other metal may be secured between the two said parts and the under surface of the said annulus may fit the lower seating to close the inlet passage. And in order that my invention may be completely understood, reference should be made to the accompanying sheet of drawings, which illustrate two examples of my invention.

Figure 1 is a central vertical section of a

part of a four stroke engine showing the new balanced valve for exhaust and inlet fitted, and the arrangement of valve gear for operating the valve. Fig. 2 is a section of a modified form of such valve to a larger scale.

Referring to Fig. 1, A is the cylinder, B the piston, C is the exhaust outlet or pipe connection. D is the upper part or exhaust end of the improved valve, D¹ its seating. D² is a recess within the engine jacket wall in which the valve is lifted to allow of its full stroke. E is the lower or inlet portion of the valve having the seating at E¹. The seating at E¹ is a similar seating to that at D¹, but a little larger in diameter, or the valve area exposed to pressure is greater. The two parts are preferably formed or cast separately. The lower or inlet end E having the ports O, O, fits as a piston within the cylindrical casing F, which has the seating E¹ at its upper edge, is screwed or fitted in the casting of the valve box, the latter being formed integrally with the cylinder. The casing F is provided as shown with the packing ring F¹ pressing inwardly upon the piston end E, but the packing ring may be dispensed with. At the lower end of the valve piston E, is a transverse bar E² cast with it. The valve stem or spindle G is formed with the head G¹, and a nut or nuts are fitted below the said bar to rigidly secure the two portions of the combined valve together. The closing cap and guide H for the valve stem G, is a close fit and is held in position by the spring. The cam J is of a known type of the desired contour to lift the valve from both of the seatings D¹ and E¹ and hold it open during the exhaust stroke of the engine to the exhaust outlet, and at the beginning of the inlet stroke to lift the valve higher closing the exhaust and hold it at its highest position, causing the ports O, O, to register with the combustion chamber, during the inlet stroke. At the end of the inlet stroke to quickly close the valve down upon its double seating the cam contour has a rapid drop or fall. The closing of the valve is effected by the spring at the drop Z of the cam, the part Y being the commencement of the exhaust lift. The motion of the cam is transmitted by the lever L fulcrumed in the crank chamber through the roller L¹. The slide or push rod L² forms the tappet for the valve. A rubber or like washer may be fitted between the valve stem and the push rod. The dotted lines above the valve indicate the position of the valve at its maximum lift. It will be observed that in this position, the shoulder D³ in the upper portion of the double valve fits within the exhaust outlet and closes it while the inlet ports are uncovered. In this position the mixture or new charge passes in below the valve and through the ports to the cylinder.

Referring to Fig. 2, the upper part D of this modified form is similar to that in Fig. 1, except that the stem is screwed into a boss below the seating D and within the valve. In lieu of the ground surface E¹ on the lower portion of the valve E, a steel or other metal disk ring K is rigidly secured between the two portions D and E of the valve and the disk K makes contact with the ground seating E¹, and the compression and explosion pressures further press the disk upon the seating. In this form also the casting is not shown and the rings are fitted in grooves in the main casting. The operation of this form is similar to that before described, when applied to a four stroke cycle engine.

This compound balanced valve for inlet and exhaust, may be operated by an ordinary eccentric mounted on the half speed shaft, Fig. 1, instead of a cam, nearly half the motion of the eccentric being lost or taken place when out of contact with the valve stem, but the cam is preferred.

A much larger valve and port area can be obtained for both inlet and exhaust without the usual corresponding objection of noise in tapping the valve open against pressure, the pressures in this valve being almost balanced. With two rings moreover or other sufficient packing, the seating on the lower or inlet end might be dispensed with. The inlet also might be arranged at the top of the valve and the outlet below if desired.

In each case the effective pressure area of the one portion of the valve is a little larger than the other, and the valve is held closed under the pressure of the combustion, by the larger area.

It will be observed that this combined or double balanced valve is distinguished by the fact that it is employed in combination with, and in order to open or close two apertures or passageways one for inlet and one for exhaust, in communication with the combustion chamber.

What I do claim as my invention and desire to secure by Letters Patent is:—

1. A valve for internal combustion engines operable to open two apertures or ports leading to the combustion chamber, one for exhaust and one for the gas or air inlet and valve seatings surrounding each of said apertures or ports by which the valve closes both of said apertures or ports.

2. A valve for internal combustion engines operable to open two apertures or ports leading to the combustion chamber, one for exhaust and the other for the gas or air inlet, valve seatings surrounding each of said apertures or ports by which the valve closes both of said apertures or ports, a valve piston carried by the valve and controlling one of said apertures or ports to the combustion chamber.

3. A valve for internal combustion engines operable to open two apertures or ports to the combustion chamber, one for exhaust and the other for the gas or air inlet, valve seatings surrounding each of said apertures or ports, by which the valve closes both of said apertures or ports, a valve piston carried by said valve for controlling one of said apertures or ports to the combustion chamber, means for moving the valve a predetermined distance to establish communication between the engine cylinder and the exhaust conduit, said means continuing the movement of the valve to establish communication between the engine cylinder and the gas or air conduit through ports arranged in the valve piston. 70
4. A valve for internal combustion engines having an exhaust aperture or port, a fuel or air aperture or port, a valve piston movable between said apertures or ports and disposed to bring the said ports or apertures into communication with the engine cylinder at different times during the stroke 85 of said valve in one direction.
5. A valve for internal combustion engines having an exhaust conduit, a fuel or air conduit, the passage to the engine cylinder being disposed between said conduits, and a valve movable between the conduits for successively bringing the conduits into register with the passage to the cylinder during the movement of the valve in one direction. 90
6. A valve for internal combustion engines in which the engine cylinder is provided with an extension or passage, a casing surrounding said extension, an exhaust conduit communicating with the passage at one side of the casing, a fuel or air conduit communicating with the passage at the other side of the casing, a valve carrying a piston supported for movement within the casing, the piston being provided with ports, means for moving the valve a predetermined distance to establish communication between the engine cylinder and the exhaust conduit, said valve actuating means continuing the movement of the valve to close communication between the engine cylinder and exhaust conduit, and establish communication between the engine cylinder and the fuel or air conduit. 100
7. A valve for internal combustion engines in which the engine cylinder is provided with an extension or passage, a casing having a passage communicating with the cylinder, an exhaust outlet arranged on one side of the casing, a fuel or air inlet arranged on the other side of the casing, a valve mounted to reciprocate within the casing and disposed during the working and compression strokes to cut off communication between the cylinder and both of said conduits, said valve when moved in one direction establishing communication between the exhaust outlet and the cylinder, the continued movement of said valve cutting off the communication between the exhaust outlet and the cylinder and establishing communication between the fuel or air inlet and the cylinder. 115
8. A valve for internal combustion engines in which the engine cylinder is provided with an extension or passage, a casing inclosing said passage, a valve seat formed on both apertures of the casing, a valve mounted to reciprocate concentrically within the apertures, the valve being provided with spaced annular members which engage the valve seats when the valve is in closed position, said members when the valve is partially raised being spaced from both valve seats, one of said annular members closing one aperture when the valve is completely raised to cut off communication between the exhaust conduit and the cylinder and establish communication between the fuel or air conduit and the cylinder through the other aperture. 130
9. A valve for internal combustion engines in which the cylinder is provided with an extension or passage, an exhaust conduit communicating with the passage at one side of the casing, a fuel or air conduit communicating with the passage at the other side of the casing, two valve seats arranged in the casing in spaced relation, a valve mounted to reciprocate between the conduits, said valve being formed with spaced annular flanges, one of said flanges being disposed to rest upon one of the valve seats, and a flexible metallic member carried by the other flange and disposed to resiliently engage the other valve seat. 140
10. A valve for internal combustion engines in which the engine cylinder is provided with an extension or passage, two apertures on opposite sides of the wall of such passage, two valve seats formed surrounding apertures in the said wall, a valve adapted to fit both seatings, an exhaust conduit communicating with one aperture, a fuel or air conduit communicating with the other aperture, the valve at one end adapted to close one aperture, a piston forming part of the valve seat adapted to close the other aperture, the said piston being provided with ports whereby communication may be established between the other or inlet aperture and the cylinder. 150
11. A valve for internal combustion engines in which the engine cylinder is provided with an extension or passage, a casing surrounding said extension, an exhaust conduit communicating with the passage at one side of the casing, a fuel or air conduit communicating with the passage at the other side of the casing, a valve carrying a piston supported for movement within the casing, 160

the piston being provided with ports, operating means for moving the valve a predetermined distance to establish communication between the engine cylinder and the exhaust conduit, said operating means continuing the movement of the valve to close communication between the engine cylinder and the exhaust conduit and establish communication between the engine cylinder and the fuel or air conduit through the ports formed in the piston.

12. A valve for internal combustion engines operable to open two apertures or ports leading to the combustion chamber, one for the exhaust and one for the gas or air inlet, and valve seatings surrounding each of said apertures or ports by which the valve closes both of said apertures or ports, and means whereby the valve is approximately balanced immediately it is lifted from its seating or seatings.

13. A valve for internal combustion engines in which the engine cylinder is provided with an extension or passage, two apertures on opposite sides of the wall of said passage, a valve seat surrounding an aperture in the said wall, a valve adapted to fit said seat, an exhaust conduit communicating with one aperture, a fuel and air conduit communicating with the other aperture, the valve at one end adapted to close one aperture, the piston forming part of the valve adapted to close the other aperture, the said piston being constructed whereby communication is established between the inlet aperture and the cylinder.

14. A valve for internal combustion engines in which the cylinder is provided with an extension or passage, an exhaust conduit communicating with the passage at one side of the casing, a fuel or air conduit communicating with the passage at the opposite portion of the casing, two valve seats arranged within the casing in spaced relation, a valve mounted to reciprocate between the conduits and on both sides thereof, said valve being formed with spaced annular flanges, one of

the flanges adapted to remain within the casing at all times and disposed to rest upon one of the valve seats, and the other of said flanges adapted to engage the second valve seat.

15. A valve for internal combustion engines in which the engine cylinder is provided with an extension or passage, a casing surrounding said extension, an exhaust conduit communicating with the passage at one side of the casing, a fuel or air conduit communicating with the passage at the other side of the casing, a valve operated by a valve stem carrying a piston arranged for movement within the casing, the piston being attached to the valve stem and provided with a port or ports therethrough, means for moving the valve a predetermined distance to establish communication between the engine cylinder and the exhaust conduit, said means continuing the movement of the valve to close communication between the engine cylinder and the exhaust conduit, and establish communication between the engine cylinder and the fuel or air conduit.

16. A valve for internal combustion engines in which the cylinder is provided with an extension or passage, an exhaust conduit communicating with the passage at one side of the casing, a fuel or air conduit communicating with the passage at the opposite portion of the casing, two valve seats arranged within the casing in spaced relation, the valve mounted to reciprocate between the conduit on both sides thereof, said valve being formed with spaced annular flanges, one of the flanges adapted to remain within the casing at all times and disposed to rest upon one of the seats, the other of said flanges adapted to engage the second valve seat, and cam means for intermittently engaging the valve stem attached to the valve for operating the said valve.
